(57) **CLAIM**

The ornamental design for a baby bed, as shown and described.

DESCRIPTION

FIG. 1 is a front view of a baby bed showing our new design; FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a perspective view thereof;

FIG. 8 is a perspective view showing the baby bed, with a front frame and a bed plate removed for convenience of illustration;

FIG. 9 is a perspective view showing the bed plate separately for convenience of illustration;

FIG. 10 is a perspective view showing the front frame separately for convenience of illustration;

FIG. 11 is a perspective view showing the baby bed, with casters removed and a pair of side frames partially folded in an alternate position, separately for convenience of illustration; and,

FIG. 12 is a perspective view showing the baby bed in a folded condition.

FIGS. 8 to 11 show respective portions of the baby bed having the overall design, separately for convenience of illustration.
